TRIMMING MACHINE

Frederic M. Card, Bridgeport, Conn., assignor to
 The Singer Manufacturing Company, Elizabeth, N. J., a corporation of New Jersey

Original application May 12, 1936, Serial No.
 79,231. Divided and this application January
 19, 1937, Serial No. 121,260

9 Claims. (Cl. 164—47)

This invention relates to improvements in trimmer mechanisms of the reciprocating-knife type, the invention having for its primary object to provide a high-speed and durable knife-actuating mechanism in a trimming machine particularly adapted for use in the production of sharply curved and smoothly trimmed work-edges.

With the above and other objects in view, as will hereinafter appear, the invention resides in the trimming and work-feeding mechanisms described in connection with the accompanying drawings, in which:

Fig. 1 is a rear side elevation, partly in section, of a machine provided with the improved trimmer-knife actuating mechanism. Fig. 2 is an enlarged front end elevation, partly in section, of the machine. Fig. 3 is a detail view in elevation of the trimmer-knife throw-in lever. Fig. 4 is a top plan view, partly in horizontal section, of the machine and the trimmer-actuating mechanism thereof. Fig. 5 represents a substantially vertical section of the counter-shaft crank and pitman. Fig. 6 represents a longitudinal section of the crank-actuated pitman, taken substantially on the line 6—6, of Fig. 5. Fig. 7 represents a transverse section of the pitman, taken substantially on the line 7—7, of Fig. 6.

As described in my co-pending patent application, Serial No. 79,231, filed May 12, 1936, of which this application is a division, the present invention as illustrated in the drawings is embodied in a sewing machine combining stitching and under-edge trimming mechanisms. However, it is to be understood that in accordance with the present invention, the thread-handling mechanisms of the sewing machine may be omitted and that the machine may be employed solely for trimming purposes.

Referring to the drawings, the machine has a frame comprising a bed-plate 1, from one end of which rises a work-supporting post 2. Upon the opposite end of the bed-plate is the supporting standard 3 of a bracket-arm 4 which terminates at its free end in a head 5 overhanging the work-supporting post 2. Journaled in the bracket-arm 4, is a horizontally disposed main actuating shaft 6 carrying at one end a combined belt-pulley and balance-wheel 7.

The work to be trimmed is advanced by a feed-wheel 8 projecting through a suitably slotted work-supporting plate 9 secured upon the upper end of the work-supporting post 2. The feed-wheel 8 may be rotated by any suitable actuating connections with the main-shaft 6, the present feed-wheel actuating mechanism being similar

to that disclosed in U. S. Patent No. 1,884,404, Oct. 25, 1932, W. C. Van Ness et al., according to which the feed-wheel is rotated at selectively different speeds to continuously advance the work. Opposed to the feed-wheel 8 is a presser-roller 10 carried by the lower end of the usual spring-depressed presser-bar 11 journaled for vertical movements in the bracket-arm head 5.

Secured, by screws 12, to the under side of the bracket-arm 4 is a trimmer bracket 13, providing bearings in which a knife-bar 14 is journaled for endwise reciprocation in a vertically inclined path. Carried by the lower end of the knife-bar 14 is a knife-holder 15 to which a work-severing element in the form of a straight-edge trimmer-knife 16 is secured by screws 17. While the cutting edge of the knife is straight, it is preferably inclined downwardly in the direction of feed, as illustrated in dotted lines in Fig. 2 of the drawings.

Suitably secured upon the knife-bar 14 is a collar 18 pivotally connected by a link 19 to an arm 20 of a bracket carried by the lower end of an actuator-bar 21. The actuator-bar 21 is confined to vertical reciprocation in suitable guide-slots 25 provided in the bracket-arm head 5, said bar 21 having in its outer edge a notch 22 adapted to receive a coupling-pin 23. The coupling-pin 23 is carried by the free end of a crank-arm 24 extending horizontally forward from one end of a rock-shaft 25 disposed substantially parallel to the main shaft 6, said rock-shaft 25 being journaled for rocking and endwise movements in bearing-lugs 26 upon the machine bracket-arm, at the rearward side thereof.

At its end opposite to the crank-arm 24, the rock-shaft 25 has a circumferential groove 27 embraced by a suitably notched ear 28 upon a trimmer throw-out hand-lever 29. The hand-lever 29 is pivotally mounted upon a horizontally disposed fulcrum-screw 30 extending transversely of the main shaft 6 and threaded into a boss 31 upon the machine bracket-arm 4. The hand-lever 29 depends below the bracket-arm 4 so as to be conveniently accessible from the front side 45 of the machine, said hand-lever being spring biased in a direction to releasably hold the coupling pin 23 in the notch 22 of the actuator-bar 21. A coil-spring 32 has its opposite ends connected to the bracket-arm 4 and to the knife-bar 14 to 50 retract said knife-bar from operative position and thereby to raise the actuator-bar 21 when the hand-lever 29 is operated to disconnect the coupling-pin from the actuator-bar 21.

Suitably secured upon the trimmer-bracket 13,

at the rearward side thereof, is an auxiliary bracket-plate 33 having its upper end spaced from the bracket 13 to receive therebetween a throw-in hand-lever for the trimmer-knife. This hand-lever comprises complementary lever-members 34, 35 pivotally mounted adjacent each other upon a stud-bolt 36. The member 34 has a laterally offset extension 37 overhanging the upper end of the lever-member 35 and to this extension is suitably secured a bent spring 38 bearing against the lever-member 35 below the pivotal axis thereof, said spring 38 functioning to yieldingly hold the lever-members 34, 35 against relative movement. The lever-member 35 of said hand-lever is yieldingly held by a spring 39 against a fixed stop-pin 40 extending inwardly from the bracket-plate 33 and determining the normal inoperative position of the hand-lever 34, 35. The offset extension 37 of the lever-member 34 is adapted to engage the upper end of the knife-bar 14 upon operation of the hand-lever 34, 35 and, as the bent spring 38 is stronger than the spring 39, the knife-bar 14 may be depressed by said hand-lever until the coupling-pin 23 enters the notch 22 in the actuator-bar 21.

However, as the throw-in movement of the knife-bar 14 serves to initiate reciprocation of the actuator-bar 21 by the rock-shaft 25, the rapidly succeeding rising movement of the knife-bar 14 with the actuator-bar 21 reacts against the hand-lever extension 37 before the member 35 of the hand-lever can be released by the operator. It is at this time, primarily, that the spring 38 functions to permit the member 34 of the hand-lever to yield relatively to the member 35, thereby absorbing the vibratory action that would otherwise be transmitted to the hand of the operator. The hand-lever member 35 is, in the present instance, provided with a headed stud 41 which serves as a steadyng guide for the lower arm of the member 34 of said hand-lever. From the foregoing description it will be understood that the trimmer-knife carrying bar 14 may be connected to and disconnected from the rock-shaft 25 at the will of the operator during the operation of the machine.

Extending rearwardly from the rock-shaft 25 and rigidly secured thereto is a forked rock-arm 42, the spaced members 43 and 44 of which are provided with horizontally alined apertures slidably receiving a pin 45 disposed substantially parallel to the rock-shaft 25. The pin 45 has a longitudinal bore 46 preferably receiving a wick 47, said bore 46 being intersected by a plurality of radial ducts 48 provided in said pin to conduct lubricant to the bearing faces in the rock-arm members 43 and 44 for the pin 45.

Rigidly secured by a screw 49 upon the slide-pin 45, between the rock-arm members 43, 44, is the apertured lower end of a vertically disposed pitman 50. At its opposite end, the pitman 50 is apertured to pivotally embrace a crank-pin 51, extending from a crank-disk 52 at one end of a rotary counter-shaft 53. The pitman 50 is restrained against movement endwise of the crank-pin 51 by a collar 54 suitably secured upon said crank-pin. The counter-shaft 53 is disposed substantially parallel to the main shaft 6 and is journaled in flanged bearing-bushings 55 and 56 suitably secured in horizontally apertured lugs 57 and 58 of a bearing-bracket 59. The bracket 59 is secured by screws 60 upon the machine bracket-arm 4 so that the counter-shaft bearing

lugs of said bracket 59 extend rearwardly from the bracket-arm 4.

Suitably secured upon one end of the counter-shaft 53 is a grooved pulley 61 connected by a belt 62 to a pulley 63 carried by the rotor-shaft 54 of an electric motor 65. The electric motor 65 is mounted upon a bracket 66 secured by screws 67 upon the rearward side of the supporting standard 3 of the sewing machine bracket-arm, said electric motor 65 being preferably provided with an electric-current controlling switch 68. The pulleys 61 and 63 are preferably proportioned so that the counter-shaft 53 is rotated at a lower rate of speed than the speed of rotation of the rotor-shaft 64.

In order to supply lubricant to the counter-shaft bearings, the bracket-lugs 57 and 58 are each provided with upstanding and vertically apertured bosses 69, the apertures 70 in said bosses (Fig. 5) being alined with lug-apertures 71 forming lubricant wells below the bushing-apertures in said lugs. Each bushing 55 or 56 is diametrically apertured to provide a restricted duct 72, connecting the boss-aperture 70 with the shaft-bearing face of the bushing, and a larger duct 73 alined with the lug-well 71. Preferably, a wick 74 is disposed in the well 71 and extends through the bushing-duct 73 into contact with the counter-shaft 53. The boss-aperture 70 is yieldingly closed at its upper end by a suitable spring-pressed valve 75, while the bushing, 55 or 56, is provided in its shaft-bearing face with intersecting spiral grooves 76. Oil introduced into the boss-aperture 70, through the valve 75, passes through the ducts 72 and 73 into the well 71, from which it is conducted by the wick 74 to the shaft and is distributed by the bushing-grooves 76 lengthwise and circumferentially of the shaft-bearing face of the bushing.

The pitman 50 is provided longitudinally thereof with a bore 77 (Fig. 6) of which the upper end is enlarged to form a reservoir 78 adjacent the crank-pin 51. Intersecting the lower portion of the reservoir 78 is a transverse pitman-bore 79 connecting said reservoir with the crank-pin bearing face of the pitman. Disposed in the transverse bore 79 is a wick 80 in wiping engagement with the crank-pin 51. The upper end of the reservoir is, preferably, yieldingly closed by a spring-pressed valve 81, while the lower end of the pitman-bore 77 is alined with a radial duct 82 provided in the tubular slide-pin 45.

Partly embracing the crank and pitman connection between the counter-shaft 53 and the rock-arm members 43, 44, is an oil-guard bracket 83 which is substantially C-shaped in vertical section, said bracket having a laterally extending shank 84 secured by screws 85 to the under side of the bracket-lug 57. The lower portion of the bracket 83 has side walls 83', thereby to provide a well for collecting lubricant thrown off by the actuating mechanism embraced by the bracket.

From the foregoing description, it will be understood that when the electric motor 65 is in operation, the rocker comprising the rock-shaft 25 and its crank-arms 24 and 42 is continuously actuated, the reciprocation of the trimmer-knife 16 being dependent upon whether or not the coupling pin 23 is in operative engagement with the actuator-bar 21. By swinging the hand-lever 29 to the right, as viewed in Fig. 1, the rock-shaft 25 is shifted endwise to disconnect the coupling-pin 23 from the actuator-bar 21. The slide-pin 45 connection between the pitman 50 and the rock-arm 42 leaves the pitman 50 un-

affected by the endwise movements of the rock-shaft 25. It will be further understood that the trimmer-knife 16 may be rendered inoperative by disconnecting the electric motor 65 from its 5 source of power, whereby the machine may be operated to advance the work without actuating any portion of the trimmer mechanism.

Having thus set forth the nature of the invention, what I claim herein is:—

- 10 1. A trimmer mechanism comprising, a reciprocatory trimmer-knife actuating bar, a rocker shiftable lengthwise of its pivotal axis into and out of operative engagement with said bar, manually operable means for axially shifting said 15 rocker, a rotary shaft, a crank-member carried by said shaft, a pitman embracing and restrained against movement axially of said crank-member, and an axially shiftable pivotal connection between said pitman and said rocker.
- 20 2. A trimmer mechanism comprising, a reciprocatory trimmer-knife actuating bar, a rocker shiftable lengthwise of its pivotal axis into and out of operative engagement with said bar, manually operable means for axially shifting said 25 rocker, a rotary shaft having its axis of rotation substantially parallel to the pivotal axis of said rocker, a crank-member carried by said shaft, a pitman embracing and restrained against movement axially of said crank-member, and an axially shiftable pivotal connection between said 30 pitman and said rocker.
- 35 3. A trimmer mechanism comprising, a reciprocatory trimmer-knife actuating bar, a rock-shaft shiftable lengthwise of the pivotal axis thereof, manually operable means for axially shifting said rock-shaft, a crank-arm carried by said rock-shaft adapted to be coupled to and disconnected from said bar, a rotary shaft disposed substantially parallel to said rock-shaft, a second crank-arm carried by said rock-shaft, and means for actuating said rock-shaft from said rotary shaft including an axially shiftable pivotal connection with said second crank-arm.
- 40 4. A trimmer mechanism comprising, a reciprocatory trimmer-knife actuating bar, a rotary shaft, a crank-member carried by said shaft, a plural-armed rocker having one of its arms operatively connected to said actuating bar, a pitman carried by said crank-member, a slide-pin carried by said pitman and having a sliding pivotal connection with another arm of said rocker, and manually operable means for shifting said 45 rocker lengthwise of the pivotal axis thereof, thereby to disconnect said rocker from said actuating bar.
- 55

5. A trimmer mechanism comprising, a reciprocatory trimmer-knife actuating bar, a rotary shaft, a crank-member carried by said shaft, a rocker operatively connected to said actuating bar and having a forked crank-arm provided with 5 alined bearing apertures, a pitman embracing said crank-member and provided with a lubricant reservoir open to the crank-member, a tubular slide-pin carried by said pitman in pivotal and endwise sliding engagement with said crank-arm, said slide-pin having radial ducts connected with said reservoir and with said crank-arm bearing apertures, and manually operable means for shifting said rocker lengthwise of the pivotal axis thereof, thereby to disconnect said rocker 15 from said actuating bar.

6. A trimmer mechanism comprising a reciprocatory trimmer-knife actuating bar, actuating mechanism for reciprocating said bar adapted to be operatively connected to said bar during the 20 operation of said mechanism, and manually operable means for operatively connecting said bar and its reciprocating mechanism including a hand-lever having members yieldable relatively to each other responsive to reciprocation of said 25 bar by said mechanism.

7. A trimmer mechanism comprising a reciprocatory trimmer-knife actuating bar, actuating mechanism for reciprocating said bar adapted to be operatively connected to said bar during the 30 operation of said mechanism, and manually operable means for operatively connecting said bar and its reciprocating mechanism including a hand-lever having complemental lever-members supported for turning movements about a 35 pivotal axis common to said lever-members, and a spring yieldingly holding said lever-members against relative movement.

8. A trimmer mechanism comprising a reciprocatory trimmer-knife actuating bar, actuating 40 mechanism for reciprocating said bar adapted to be operatively connected to said bar during the operation of said mechanism, a member manually operable to couple said bar and its actuating mechanism, and means interposed between 45 said member and said bar yieldable responsively to reciprocation of said bar by said mechanism.

9. A trimmer mechanism comprising a reciprocatory trimmer-knife actuating bar, an actuating element adapted to be operatively connected to reciprocate said bar, means for shifting said bar into position for engagement by said actuating element including a manually operable member, and means yieldingly interposed between 50 said member and said bar.
